UNITED STATES PATENT OFFICE

JULIUS BECKER, OF SYRACUSE, NEW YORK, ASSIGNOR TO SEMET-SOLVAY ENGINEERING CORPORATION, OF SOLVAY, NEW YORK, A CORPORATION OF NEW YORK

FLUE SYSTEM FOR RETORT COKE OVENS

Application filed September 19, 1921. Serial No. 501,577.

My invention relates generally to coke ovens having horizontally disposed heating flues and more particularly to ovens of this class which are provided with two sets of flues on each side of the oven separated by a dividing wall and the object of my improvements is to provide a simple and economical form of construction, and at the same time to give a more perfect control of the oven heating operation.

In carrying my invention into effect I provide on each side of a coke oven two independent sets of heating flues. Each of the sets of flues on one side of the oven is connected with the oppositely located set on the other side of the oven, so that the two sets form independent heating units, and each of these heating units is connected with its own set of regenerators. Thus, while obtaining an efficient heat supply for the whole oven, I provide for the independent regulation of the temperature of the two ends thereof, as is frequently desirable.

The invention will be best understood by reference to the accompanying drawings illustrating an embodiment thereof, Fig. 1 of which shows an end view of a battery of coke ovens, partly broken away and depicted in section to show the heating flues; Fig. 2 shows a vertical cross section through the oven and heating flues on the line 2—2 of Fig. 1, and Fig. 3 shows a horizontal sectional view of a single oven taken on the line 3—3 of Fig. 1.

Referring to the drawings, A, indicates the coking chamber, on each side of which are two sets of independently operative heating flues, B, B' which are located in dividing walls between the coking chambers and are separated by a dividing wall W.

Below each oven and its heating flues are two sets of regenerators, C, C', D, D', of the usual checker work brick construction, and below the regenerators are flues E, E', F, F', disposed longitudinally of the battery of ovens for the conduction of air to and the reception of the hot gases of combustion from the regenerators. The flues E, F', are connected together at the reversing valve

(not shown in the drawings) as are also the flues E', F.

The flues E, F', are connected by passages a, b, with regenerators C, D', and the flues E', F, are connected by passages c, d, with regenerators C', D. The regenerators C, D', are respectively connected by ports e, f, with sole flues, G, G', located under the chamber or in the bottom wall of the coking chamber A, each of which extends the length of one

55

of the sets of heating flues, B, B', and which are separated by the dividing wall W.

The sole flues G, G', are respectively connected by ports g, g', and conduits 12 with the lowermost flues, 1, of the two sets of heating flues B, B', on one side of the oven, and the corresponding lowermost flues of the two sets of heating flues on the other side of the oven are connected by passages or conduits h, h, with the regenerators C', D. The uppermost flues 6, of the two sets of heating flues, B, B', on one side of the oven are connected by cross-over flues or passages H, H', which pass through the brickwork above the oven, or through the top wall defining the chamber and communicate with the uppermost flues of the corresponding sets of flues on the opposite side of the oven.

75

When the oven is in operation and air enters through the flues E, F', which are connected at the reversing valve and act as a single flue, the air from the flues E, F', enters the regenerators C, D', through the passages a, b, and thence by ports e, f, into the sole flues G, G'. From the sole flues G, G', the air enters the lower heating flues 1, 1, by ports g, g', and rises through the heating flues to the uppermost flues 6, 6, whence it crosses by transverse passages H, H', to the other side of the oven entering the corresponding uppermost heating flues on that side and passes down through the heating flues. In passing through the flues the air supports the combustion of fuel gas issuing from burners 10 which are associated with the heating flues and which are connected to fuel gas supply pipes 11. The hot gases of combustion pass from the lowermost heating flues, 1', by passages h, h, to regenerators

80

85

90

95

100

C', D, and thence by passages c, d, to flues E', F, and through these to the stack.

On the reversal the air, entering from flues E', F, passes into regenerators, C', D, and thence by passages h, into the lowermost heating flues 1', and upward through the heating flues to the upper flue 6', whence it crosses over by passages H, H', to the upper heating flue 6, on the other side of the oven, and passes downward through the heating flues. The hot gases of combustion pass from the lower heating flues 1, 1, by ports, g, g', into sole flues G, G', and from the sole flues by ports e, f, into regenerators C, D', and thence by passages a, b, to flues E, F', and to the stack.

From the foregoing it will be evident that the flow of gases through each of the two sets of heating flues B, B', is independent of that through the other and the temperatures of the two ends of the oven can be separately controlled and regulated. Moreover, since a separate regenerator is provided for each half of the oven the dividing of the air current in the regenerator, as at present is eliminated.

Having thus described my invention, what I claim as new and desire to secure by Letters Patent is:—

- 30 1. A coke oven comprising in combination a horizontally elongated coking chamber, two independent heating systems for said coking chamber, one of said heating systems extending a portion of the length of said chamber, and the second of said heating systems extending for another portion of said coking chamber, each of said heating systems comprising the hereinafter recited flues, passages, conduits, and regenerators, to wit, a combustion flue on each of opposite sides of said coking chamber, each of the combustion flues comprising zig-zag series-connected superimposed horizontal passages, a cross-over flue extending over the top of said coking chamber and communicating with each of the uppermost of said horizontal passages on opposite sides of said coking chamber, each of the lower-most of said horizontal passages on opposite sides of said coking chamber, and four reversible regenerators arranged in a row beneath the coking chamber longitudinally thereof and communicating with the flues.
- 40 2. In a coke oven, a horizontally elongated coking chamber, a heating system for said coking chamber comprising a combustion flue on opposite sides of said coking chamber, each of the combustion flues comprising zig-zag series-connected superimposed horizontal passages, a cross-over flue extending over the top of said coking chamber and communicating with each of the uppermost of said horizontal passages on opposite sides of said coking chamber, a pair of reversible regen-

erators positioned beneath said coking chamber parallel thereto, the individual members of said pair being positioned in alignment longitudinally of said coking chamber, a conduit individual to and communicating with the lowermost of said horizontal passages on one side of said coking chamber and with one of said pair of regenerators and a second conduit individual to and communicating with the lowermost of said horizontal passages on the other side of said coking chamber and with the other of said pair of regenerators.

3. A coke oven battery comprising horizontally elongated coking chambers and heating walls therefor arranged side-by-side in alternate relation, each of said heating walls being composed of four sets of zig-zag series-connected superimposed horizontal passages arranged in groups of two disposed adjacent the side of each coking chamber, cross-over flues extending over the tops of said coking chambers and communicating with each of the uppermost of said two groups of horizontal passages on opposite sides of each coking chamber, reversible regenerators disposed in groups, each of said groups having four regenerators in a row, each of said coking chambers having one of the rows of regenerators therebeneath and parallel therewith, each of said rows of regenerators being individual to and communicating with the lowermost horizontal passages of the two sets of horizontal passages on opposite sides of the coking chamber thereabove.

4. A coke oven battery comprising horizontally elongated coking chambers and heating walls therefor arranged side-by-side in alternate relation, each of said heating walls being composed of four sets of zigzag series-connected superimposed horizontal passages arranged in groups of two disposed in longitudinal alignment adjacent the side of each coking chamber, cross-over flues extending over the tops of said coking chambers and communicating with each of the uppermost of said two groups of horizontal passages on opposite sides of each coking chamber, reversible regenerators disposed in groups of four regenerators, each of said coking chambers having one of said groups therebeneath and the regenerators in the group being arranged in alignment longitudinal of the coking chamber thereabove, each of said groups of four regenerators being individual to and communicating with the lowermost horizontal passages of the two sets of horizontal passages on opposite sides of the coking chamber thereabove.

In testimony whereof I affix my signature, this 15th day of September, 1921.

JULIUS BECKER.
